Fred H. O'Hara, Norwich, N. Y.

Application February 14, 1942, Serial No. 105,817

Term of patent 3½ years

To all whom it may concern:

Be it known that Fred H. O'Hara, a citizen of United States and resident of Norwich, in the county of Chenango and State of New York, has invented a new, original, and ornamental Design for a Shirt or Similar Article, of which the following is a specification, reference being had to the accompanying drawing, forming part thereof, and in which,

The single figure of the drawing is a front view of a shirt, embodying my new design.

The rear of the shirt is the same as the front, without the design which appears on the chest portion of the shirt.

The characteristic features of my design reside in the combination on the shirt disclosed of the specific airplane, cloud and battleship decoration arranged on the front as shown.

I claim:

The ornamental design for a shirt or similar article, substantially as shown and described.

FRED H. O'HARA.
